ORPHREY OR SIMILAR ARTICLE

Charles M. Muench, New York, N. Y.

Application September 22, 1953, Serial No. 26,903

Term of patent 3½ years

(Cl. D3—32)

To all whom it may concern:

Be it known that I, Charles M. Muench, a citizen of the United States of America, residing in New York city, county and State of New York, have invented a new, original, and ornamental Design for an Orphrey or Similar Article, of which the following is a specification, reference being had to the accompanying drawing, forming part thereof:

In the drawing the figure is a plan view of the orphrey embodying my design. The design unit which is shown between the dot and dash lines is repeated in regular succession along the length of the fabric.

I claim:

The ornamental design for an orphrey or similar article, substantially as shown.

CHARLES M. MUEENCH.
